FEEDING MECHANISM

Ferdinand Autenrieth, Irvington, and Carl F. Riedl, Hasbrouck Heights, N. J., assignors to C. F. Mueller Company, Jersey City, N. J., a corporation of Delaware

Application July 26, 1950, Serial No. 175,922

7 Claims. (Cl. 198—37)

1

This invention relates to a structurally and functionally improved feeding mechanism and especially a mechanism through which articles such as food products may be fed towards weighing assemblies and packaging mechanisms.

It is a primary object of this invention to provide an apparatus by means of which products will be evenly and properly fed without piling up. Accordingly, these products may be distributed in the form of units of predetermined quantity without danger of jamming the machine and consequent interruption in the operation of the weighing mechanism. Also, wastage and spoilage of quantities of the products is thus avoided.

Among other objects are those of furnishing an apparatus which when once set in operation will require substantially no manual supervision; the assembly embracing relatively few parts, each individually simple and rugged in construction, such parts being capable of ready disposition with respect to each other to furnish a satisfactory mechanism which will operate over long periods of time with freedom from all difficulties.

With these and other objects in mind, reference is had to the attached sheets of drawings illustrating one practical embodiment of the invention, and in which:

Fig. 1 is a side elevation of the mechanism with certain of the parts broken away to disclose underlying structures, other parts having been shown in section;

Fig. 2 is a front elevation taken along the lines 2—2 and in the direction of the arrows as indicated in Fig. 1;

Fig. 3 is an enlarged fragmentary transverse sectional view taken along the lines 3—3 and in the direction of the arrows as also indicated in Fig. 1; and

Fig. 4 is a somewhat diagrammatic view showing the general control and wiring circuits which may be incorporated in the apparatus.

With primary reference to Figs. 1 and 2, the numeral 10 indicates the supporting frame of the mechanism adjacent the upper end of which a deck 11 is mounted. Above the deck 11 a conveyor 12 may be disposed to pass around a supporting roller 13. This conveyor is driven by, for example, a motor 14 which may be supported upon deck 11. Disposed adjacent the lower end of frame 10 is a more or less conventional and standard weighing mechanism 15. The latter may, as shown, embrace a grouping of six units, each provided with a standard cut-off structure 16. These units are conveniently disposed above

2

a conveyor (not shown) upon which cartons 17 may move. These cartons define the ultimate packages or receptacles to receive the products.

Such products are conveniently spaghetti, noodles, macaroni, etc., although it is apparent that other products might be handled by the present mechanism. It will likewise be understood that in lieu of the weighing mechanism as indicated, other apparatus might be employed. Additionally, a feeding conveyor different from that indicated at 12 might be employed and a driving motor therefor need not necessarily be mounted upon the frame or deck of the apparatus. Therefore, except where otherwise indicated in the appended claims, the general layout of mechanism as herein described is to be taken in an illustrative, rather than in a limiting sense.

Adjacent the discharge end of conveyor 12 a receiving member in the form of a funnel 18 may be disposed. That funnel is provided with a neck portion 19 from which a spout 20 extends downwardly. These parts may be supported by a plate 21 mounted on anti-friction bearings 22 and a block or collar 23 supported upon deck 11. A motor 24 also conveniently supported upon that deck may serve to drive a cam 25 through a reduction gearing within a housing 26. A follower 27 bears against the edge of the cam and is mounted upon an arm 28 pivotally supported upon deck 11 as at 29 and connected to a crank or link 30 which is, in turn, connected to plate 21. Therefore, when motor 24 operates plate 21 will be oscillated to correspondingly move spout 20.

This spout discharges into the upper end of an inclined tray 31 which is supported by links 32 or in any other desirable manner from the lower face of deck 11. Also suspended from the lower face of that deck by means of brackets 33 or other mounting structure are control shafts 34 and 35. The latter carry downwardly extending fingers or projections 36 the length of which is such that they clear the upper surface of tray 31. Also, each of these shafts supports a switch 37. Conveniently below the lower surface of tray 31 vibrating units such as 38 and 39 of any desired structure, may be secured. These units are, for example, of a type which, when connected to a source of alternating current, will set up vibrations incident to the passage of that current through their assemblies. Obviously the units might include vibratory armature structures which, together with interrupters, will subject the tray 31 to a continuous vibrating action.

Adjacent the lower or discharge end of tray 31

a mounting shaft 40 may be supported. That shaft as especially shown in Fig. 3 rotatably carries a series of sleeves 41. As illustrated, these sleeves are six in number and each of them conveniently carries a sprocket 42 which by means of a suitable drive is connected to a motor 43. From each of sleeves 41 feeding fingers or combs 44 extend outwardly. Conveniently these take the form of a series of wire fingers. As shown particularly in Fig. 2 six of these feeding assemblies may be mounted upon shaft 40 and due to the provision of motors 43 one or more of the sleeves may be operated as hereinafter brought out.

Below the delivery end of tray 31 are a series of chutes 44 which again may be six in number. These chutes are conveniently mounted by pivots 45 adjacent their inner ends. The chutes are supported in inclined position and have their outer ends connected to springs 46 which are also attached to the frame 10. Conveniently in contact with the lower faces of chutes 44 are units 47. The latter serve to individually vibrate the chutes and are more or less identical with units 38 and 39 as heretofore described.

In order to support chute members 48 one adjacent the delivery end of each of chutes 44, frame 10 may carry an extension 49. Pivotally mounted upon this extension are a pair of links 50 which have their upper ends pivotally coupled to the lower face of an individual chute 48. Vibrating units 51 are connected one to each of chutes 48 in order to subject the latter to agitation; such connecting being conveniently achieved by mounting the units 51 on one of the pair of links 50 of a chute assembly. Rotatably mounted control members 52 are supported above chutes 48. Flaps may be mounted by these control members and have been indicated at 53. These flaps extend closely adjacent the bases of the chutes and when shifted serve to also shift a switch 54 mounted by the control member.

The delivery ends of chute members 48 extend in operative relationship with respect to the units 15 of the weighing or other mechanism. The receiving end of the latter units may be defined by hoppers 55. Conveniently an operating link 56 extends from each unit 15 and is connected by a crank 57 to a shaft and gear assembly by means of which a shaft 58 may be rocked. The latter supports switch units 59 and 60. In common with the switch units 37 and 54, switches 59 and 60 are conveniently of the mercury type.

As shown especially in Fig. 4 power supply leads 61 and 62 may be provided with branches connecting the several electrical units of the apparatus. Thus, switch 59 may control the operation of vibrator 47 associated with a delivery chute member 44. If switch 63 controlled by link 56 is in closed position then either the opening of switch 54 or switch 60 will interrupt the operation of a given drive motor 43. Of course, if switch 63 is in open position, then, even if switches 54 and 60 are closed, no operation of that motor will occur. With both of the switches 37 connected to controls 34 and 35 closed, the spout-oscillating motor 24 as well as the conveyor driving motor 14 will be operated. With either of these switches open both motors will cease to function. Conveniently units 38 and 39 are controlled by manually operated switches 64. It is apparent that switches which are otherwise operated might be employed.

In operation it will be assumed that the parts are assembled in the manner shown in Fig. 1. It will also be assumed that goods are being de-

livered by conveyor 12 and that cartons or packages 17 are being fed in properly timed relationship below the delivery ends of weighing or equivalent mechanisms 15. Under these circumstances the goods will be discharged into funnel or hopper 18. As spout 20 oscillates the goods will be distributed throughout the upper zone of tray 31. Due to the fact that the latter is inclined and subjected to constant vibration the material will spread and pass towards the lower or delivery end of that tray. Adjacent that delivery end it will be impelled by comb or fingers 44 into the series of delivery chutes 44. The latter being inclined, preferably pivoted and subjected to vibration the material will therefore move throughout the lengths of chutes 44 into chutes 48 which they overlap. Again in this zone the goods will pass towards the hoppers 55 of the mechanism or units 15. In this connection it will be remembered that chutes 48 are also subjected to vibration and are supported for limited movement so that uniform distribution and spread of maximum efficiency results.

When one of the units 15 receives a pre-determined amount of the goods, then that body of material should be delivered to the carton 17. Under these circumstances the cut-off 16 will automatically function. With such functioning, switch 63 as well as switches 59 and 60 will be operated. Due to the opening of switch 59 the vibrator 47 associated with a corresponding chute 44 will cease to function. Also the vibrator 51 will be rendered inoperative. As a consequence of opening of the switches 60 and 63 the aligned impelling mechanism embracing sleeve 41 and fingers 44 will cease to operate because of the interruption of drive of motor 43. Therefore a continuing feed of material towards the hopper 55 will not occur as the cut-off of the weighing mechanism functions. Also, if material within delivery chute 48 or an aligned chute and unit is caused to function incident to goods piling up in that chute and causing an oscillation of flap 53 and switch 54, an interruption of driving force will occur.

Assuming that material piles up in tray 31 this will initially be evidenced by control 34 being oscillated. With such movement of the parts the switch 37 connected to that control will open. This will cause an immediate cessation of operation of motors 14 and 24. Therefore, the feeding of material will be discontinued. The same is true of the opening of switch 37 connected to control 35. However, under these circumstances, vibrator units 38 and 39 will continue to function. Accordingly, the surplus material which has accumulated in tray 31 will be fed down the surface of that tray and delivered into chutes 44 and 48 so as to relieve the congested condition within the tray 31. As soon as that congestion is relieved, as will be evidenced by controls 36 returning to their normal position, the circuits through motors 14 and 24 will be closed and material will continue to be delivered to hopper or funnel 18 and be distributed by the spout 20 of the latter throughout the area of the upper surface of tray 31.

Thus, among others, the several objects of the invention as specifically aforesaid are achieved. Obviously, numerous changes in construction and rearrangements of the parts might be resorted to without departing from the spirit of the invention as defined by the claims.

We claim:

1. A feeding mechanism including in combination a spout, a support therefor, a funnel

mounted by said spout, a tray movably mounted by said support at a point below said funnel, means for vibrating said tray, means for movably supporting said spout for oscillation over said tray, a power mechanism, a link pivotally connected to said spout, a rockably supported member pivotally connected to said link, a cam cooperative with said member for rocking the latter and means for connecting said cam with said power mechanism.

2. A feeding mechanism including in combination a spout, a support therefor, a funnel mounted by said spout, a tray movably mounted by said support at a point below said funnel, means for vibrating said tray, means for moving said spout over the surface of the tray, the body of the latter being disposed in an inclined plane, a plurality of chutes disposed adjacent the lower end of and below the tray to receive material therefrom, impelling means individual to each of said chutes for effecting transfer of material from said tray to said chutes and means for operating said impelling means.

3. A feeding mechanism including in combination a spout, a support therefor, a funnel mounted by said spout, a tray movably mounted by said support at a point below said funnel, means for vibrating said tray, means for moving said spout over the surface of the tray, the body of the latter being disposed in an inclined plane, a plurality of chutes disposed adjacent the lower end of and below the tray to receive material therefrom, impelling means individual to each of said chutes for effecting transfer of material from said tray to said chutes, means for operating said impelling means and means responsive to a flow of material through said chutes for controlling the functioning of said operating means.

4. A feeding mechanism including in combination a supporting structure, a funnel carried by said structure and to receive material to be fed, a spout receiving material from said funnel and mounted for movement, power means for oscillating said spout, a tray to receive material distributed by said spout, means responsive to a flow of material through said tray to control the operation of said power means and a chute receiving material from said tray.

5. A feeding mechanism including in combination a supporting structure, a funnel carried by said structure and to receive material to be fed, a spout receiving material from said funnel and mounted for movement, power means for oscillating said spout, a tray to receive material dis-

tributed by said spout, means responsive to a flow of material through said tray to control the operation of said power means, means for vibrating said tray, a plurality of chutes disposed below said tray to receive material therefrom and means for vibrating said chutes.

6. A feeding mechanism including in combination a support, a hopper extending above said support, an oscillatable spout mounted below said support to receive and distribute material delivered to said hopper, an inclined tray movably mounted by said support, said spout having an arc of movement between the side edges of said tray and extending in a direction opposed to the direction of movement of material over the surface of the tray after such material has been delivered thereto by said spout, a plurality of inclined trays mounted adjacent each other below said first named tray to each receive material therefrom and means for vibrating all of said trays.

7. A feeding mechanism including in combination a support, a hopper extending above said support, an oscillatable spout mounted below said support to receive and distribute material delivered to said hopper, an inclined tray movably mounted by said support, said spout having an arc of movement between the side edges of said tray, a plurality of inclined trays mounted below and receiving material from said first named tray and a plurality of impelling means corresponding in number to the number of last mentioned trays and disposed adjacent the lower edge of said first named tray for transferring material from the latter to each of said plurality of trays.
